UNITED STATES PATENT OFFICE

2,446,095

FEED GRINDING MILL OF THE ROTARY
BEATER TYPE

Gustaf E. Miller, Stratton, Nebr.

Application January 25, 1945, Serial No. 574,503

1. Claim. (Cl. 241—189)

This invention relates to a feed grinding mill for grinding and elevating stock feed and ensilage. The principal object of the invention is to provide an exceedingly simple and highly efficient grinding device which will have a maximum output for a minimum of power.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view of the improved feed grinding mill; and

Fig. 2 is a cross section therethrough.

The entire mill is formed from standard structural materials and does not require special castings, shapes, and the like. It comprises a rectangular grinding chamber formed from two side plates 10 and 11, two end plates 12 and 13, and a bottom plate 14. A plurality of tie bolts 16 pass through the two end plates 12 and 13 to clamp the entire structure together. When the bolts 16 are tightened, the side and bottom plates 10, 11, and 14 are firmly clamped between the end plates. The internal pressure forces the side plates outwardly against the bolts.

The end plates 13 are flanged outwardly at their bottoms as shown at 17, so that they may hook beneath base bolts 18, which extend between angle frame members 19. A shaft bracket member 20 is also clamped between the base members 19 by means of a third base bolt 21.

A stationary shaft rod 22 extends between the end plate 13 and the bracket 20, passing through an air intake opening 23 in the end plate 12. The rod 22 is locked in place by means of suitable lock nuts 24. A tubular shaft sleeve 25 surrounds the rod 22 and is rotatably mounted thereon upon suitable anti-friction bearings 26. Two beater blades 27 are welded to the opposite sides of the shaft sleeve 25 and extend equally outward therefrom in parallel relation. These blades are of slightly less length than the length of the side plates 10 and 11 so that they may rotate freely therebetween.

A sheet metal hopper 28 is fitted into the top of the grinding chamber, and is secured to an upwardly projecting lip 29 on the end plates by means of suitable attachment bolts 30. The hop-

per 28 is formed with an inclined bottom plate 29 extending over the top of the grinding chamber.

The hopper 28 covers about one-half of the top of the beater housing. A discharge head 32 covers the remainder of the top of the chamber beneath the inclined bottom plate 31.

A conveyor tube 33 of any desired length, depending upon where the ground feed is to be deposited, is telescoped over the extremity of the discharge head 32 and is secured in place between clamping bars 34 and 35 by means of suitable clamping bolts 36. The bar 35 is riveted or otherwise secured to the inclined bottom plate 31.

A gate plate 37 is slidable within the hopper 28 so that it can be inserted to contact the plate 31 to shut off the supply of material to the beater chamber. This plate can be drawn outwardly to provide any desired feed opening or throat, and can be locked or clamped in its final adjusted position by means of a clamp bolt 38 and clamp nuts 39.

A first breaker bar 40 is welded or otherwise secured across the lower part of the side plate 10, and a second breaker bar 41 is welded or otherwise secured across the bottom plate 14. The bars 40 and 41 are positioned closely adjacent to the peripheral path of the beater blades 27.

In use, the material to be ground is fed into the hopper 28 and flows through the throat between the plate 37 and the plate 31 to the rapidly revolving beater blades 27. These latter blades first throw the material against the side plate 10, thence against the breaker bar 40, thence against the bottom plate 14, thence against the breaker bar 41, thence against the side plate 11, and then into the discharge head 31. This plurality of impacts combined with the high speed of rotation of the beater blades 27 results in a rapid and efficient attrition of the material, and discharges it at high velocity from the discharge head 31.

The beater blades 27 act as a blower as well as a beater, the air being taken in through the intake opening 23 in the end plate 12 and blown with the ground material from the discharge tube 32.

It will be noted that a portion of the shaft sleeve 25 projects beyond the end plate 12 to serve as a belt pulley for driving the beater blades.

While a specific form of the improvement has been described and illustrated herein, it is desired to be understood that the same may be varied, within the scope of the appended claim,

without departing from the spirit of the invention.

Having thus described the invention, what is claimed and desired secured by Letters Patent is:

A grinding mill comprising: two side plates; two end plates; a bottom plate; a plurality of bolts extending between said two end plates and clamping the latter against the ends of said side and bottom plates; said bolts being positioned against the outer faces of said side plates to prevent outward movement of the latter; a pair of angle frame members receiving the bottom corners of said end plates and extending parallel to said side plates and having projecting extremities extending beyond one end plate; a shaft bracket member positioned between the projecting extremities of said angle frame members; means clamping said latter members against the side edges of said end plates and against said shaft bracket member to support the latter; a stationary shaft rod extending from the end plate more distant from the bracket member through said mill to said shaft bracket member; means fixedly securing said rod to said more distant plate and to said bracket member; a tubular shaft sleeve rotatably mounted on said stationary rod;

and of a length substantially equal to that of the rod; and a beater blade secured to each side of said tubular shaft sleeve said blades extending equally outward from said shaft in parallel relation between said end plates.
